UNITED STATES PATENT OFFICE.

FRED D. LYONS, OF KANSAS CITY, MISSOURI, ASSIGNOR TO IZORA M. LYONS.

OIL BURNER.

Application filed March 29, 1926. Serial No. 98,214.

The present invention relates to burners, and more especially to burners using oil as a fuel, and aims to provide an improved construction having a reinforcing feature to eliminate defects due to warping, and also including novel provision for lending support to the packing construction employed when the burner is mounted in position within a fire box.

Accordingly, I have devised a burner which includes a base casting and the usual burner bowl and air supply conduit members in combination with a skeleton casting member so mounted as to embrace the ends of the air supply member to reinforce the same against warping tendencies.

In further carrying out the objects of the invention, I have devised a base casting formed with a suitable supporting flange extending entirely around the burner structure, and adapted to afford a support for the packing construction used around the burner when placed inside a fire pot.

With these general objects in view, as well as minor objects as will appear in the course of the detailed description, the invention will now be set forth in detail in connection with the accompanying drawing illustrating one form of construction which I have devised for embodying the proposed improvements, after which those features deemed to be novel will be particularly set forth and claimed.

In the drawing—

Figure 1 is a vertical sectional view, of the fire pot portion of a furnace, and illustrating in elevation a burner construction embodying the present invention, in its proper relation to said fire pot;

Figures 2 and 3 are top and bottom plan views, respectively, of the burner structure;

Figures 4 and 5 are transverse sections, taken on the lines IV—IV and V—V, respectively, of Figure 2; and

Figure 6 is a side elevation of the burner structure, taken at right angles to the view of said burner shown in Figure 1, and a portion of the reinforcing ring being broken away.

Referring now to the drawing in detail, this illustrates the improved burner as comprising a base or supporting casting 10 of substantially ring-shape formed with internal slightly upturned flanges 12 for air deflecting purposes, as hereinafter explained. The lower margin of said base casting is pro-

vided with an outwardly projecting flange 14 to the lower face of which are attached suitable supporting legs 15, necessary for mounting the burner structure at the proper height within the fire bowl or pot 16, as shown in Figure 1. In practice, it is also necessary to provide a substantially airtight partition between the space around the burner above said flange 14, and the space within the fire pot below said flange, for which purpose suitable packing material 17 is spread upon a supporting plate 18, the outer margin of which is rested upon lugs 19 projecting inward from the fire bowl 16, and, in the present construction, the supporting flange 14 affords a sure and convenient supporting ledge for the inner margin of this plate 18 and the packing material 17 carried thereby, around the base casting. 75

Within this base casting 10 is mounted the usual burner bowl member 20, the upper and outer margin of which is formed with a supporting flange 21 resting upon the upper edge of the casting 10, as clearly shown in Figure 5. The oil supply is conducted to this bowl by means of the usual inlet pipe 22 to the approximately cone-shaped central portion 23 of the bowl, where the oil discharges upon the upper exterior face of this central portion 23, which in the present construction is formed with a spiral channel 24 extending from the top of the portion 23 to the bottom of the bowl 20 (see Figures 2 and 5). In this way, 85 a continuous channel is formed from the outlet point of the pipe 22 to the bottom of the bowl, so that a uniform flow of any oil not immediately vaporized is produced by means of this spiral channel arrangement. 95

At opposite sides of the burner bowl 20 is formed a pair of approximately triangular air intake ports 26 whereby air is conducted from below the burner through the 100 base supporting casting 10 and upward through the passages 26 formed within the bowl 20, from which points the air flows into the ends of an arched air supply conduit member 28. The ends or receiving 105 points of this conduit member 28 are also approximately triangular shaped, for fitting over the upper margins of the passages 26, as indicated in Figure 4; the extreme end edges of the air conduit member 28 project 110 slightly lower than the upper margins of the passages 26 into shallow depressions 30

cut in the upper margin of the base casting 10, whereby the latter cooperates with the burner bowl member 20 in supporting the air conduit member, as shown in Figure 6. By this construction, the air employed for supporting combustion is preheated in the usual manner by being carried through the flame zone and discharged through an outlet opening 32 directly over the oil outlet, as seen in Figure 4. Referring to Figure 3, it will be noted that the interior flanges 12 of the base casting 10 are located on opposite sides of the air passages 26, the object of these flanges 12 being to direct the flow of air from below the casting 10 up through said passages 26; and, in addition, these flanges serve to maintain the burner bowl member 20 in the particular position illustrated.

20 The usual oil overflow pipe 32 is provided and connected with the burner bowl at the proper point for conducting off any excess oil which may be overflowing therefrom.

On its exterior face, the base supporting casting 10 is formed with a series of lugs 34 the upper edges of which form supporting ledges or shoulders positioned somewhat below the upper margin of the casting 10 as well as slightly below the base of the depressions 30, as shown in Figure 6. These lugs are for the purpose of supporting a reinforcing ring 36 which is formed with a reinforcing flange 37, the size of this ring 36 being such as to embrace the lower end portions of the air conduit member 28. Thus the ring 36 not only seals the meeting line between the base casting 10 and the ends of the conduit member, but also serves to strengthen and reinforce the latter against any warping tendencies under the influence of high temperatures, which ordinarily cause the air supply conduit to become distorted and hence to open up air leaks around the joints between it and the rest of the burner, with resultant inefficient operation of the burner.

It will thus be apparent that I have devised a practical and efficient burner con-

struction for carrying out the desired objects of the invention. The flange feature 59 14 provided in connection with the base supporting casting not only strengthens this portion of the burner, but affords a positive and permanent support for the packing material directly around the base of the 55 burner. Further, the provision of the reinforcing ring 36 prolongs greatly the life of the burner due to its protection of the air supply conduit, and maintains the efficiency of the burner for a much longer 60 period than is true of the burners of this particular type now in common use.

While I have illustrated and described what I now regard as the preferred form of embodiment of the invention, I desire to 65 expressly reserve the right to make all such changes or modifications as may fairly fall within the scope of the appended claims.

What I claim is:

1. An oil burner construction comprising 70 a base casting provided with an external supporting flange, packing material supported by said flange, said casting being also provided with external supporting lugs above said flange, a burner bowl and an 75 arched air supply conduit supported by said casting, and an annular reinforcing member supported above said packing by said lugs and embracing the ends of said air supply conduit.

2. An oil burner construction comprising 80 a base casting provided with an external flange, a packing having its inner margin supported by said flange, said casting being also provided with lugs forming supporting 85 ledges slightly below the upper margin of said casting, a burner bowl and an arched air supply conduit supported by the upper margin of said casting and an annular reinforcing member supported above said 90 packing by said lugs and embracing the ends of said air supply conduit.

In witness whereof I hereunto affix my signature.

FRED D. LYONS.
